RULER USED IN MATHEMATICS

Don C. Cherrington, 862 Birdhaven Court,
Lafayette, Calif. 94549

Filed May 17, 1966, Ser. No. 2,337

Term of patent 14 years

(Cl. D52—6)

FIG. 1

FIG. 2

FIG. 3

FIG. 1 is a plan view showing my ruler used in mathematics. The bottom plan view is similar in outline and if made of transparent material the lettering and symbols are shown reversed.

FIG. 2 is a side elevation thereof.

FIG. 3 is an end elevation thereof.

I claim:

The ornamental design for a ruler used in mathematics, as shown and described.
